UNITED STATES PATENT OFFICE

MATTHIAS LEWIS WILKINSON AND ROBERT BRADSHAW, OF PRESTON, ENGLAND

LOCKING OF STEREOPLATES OR PRINTING SURFACES TO THE CYLINDERS OF ROTARY PRINTING MACHINES

Application filed March 25, 1931, Serial No. 525,280, and in Great Britain April 1, 1930.

This invention relates to improved means for locking stereo plates or printing surfaces to the cylinders of rotary printing machines.

In the case of four plate wide rotary printing presses it is usual to secure the plates by utilizing the centre margin ring as an abutment for the inner sides of the two inner plates, then to engage the outer sides of the inner plates by means of dogs sliding in grooves or dog-ways in the cylinder, then to fit the two outside plates with their inner edges against the dogs and finally to press the outer edges of the outside plates towards the dogs by means of outer dogs which are then locked in position. Thus the inner plates are locked through the medium of the outer plates. The dogs engaging the inner plates in this arrangement are pushed into position individually by hand while the dogs engaging the outer sides of the outside plates are operated by screwed rods mounted in the end plates of the cylinder. The rods are fitted with gear wheels which gear with other wheels carried on the end plates so that on turning one of the rods all the rods relating to a particular set of plates are turned.

With this arrangement, if it is desired to remove the inner plate from one half of the cylinder this can only be done by first releasing the outer plate and leaving it unsecured. Since the outer plate is unsecured the cylinder cannot be turned to attend to a plate on the diametrically opposite side and the outer plate must also be removed. This is a disadvantage in practice and in addition certain of the dogs must be operated individually by hand.

The present invention has for its object to provide improved locking means wherein the moving of individual dogs by hand is obviated and whereby the plates may be locked independently, thus overcoming the disadvantages referred to above. According to the invention, the locking arrangement is such that the necessary dogs are all operated by screwed rods or the like from the ends of the cylinder and there is no necessity to move any of the dogs individually by hand. The outside plates with their locking

dogs can be moved to release the inner plates without unlocking them or removing them so that the inner plates can be removed and the cylinder rotated without fear of the outer plates becoming displaced. The inner and the outer plates are locked independently.

The invention also includes an arrangement which is applicable for securing stereo plates wherein the number of columns is variable.

Several suitable constructions for carrying out the invention will now be described by reference to the accompanying drawings in which:

Fig. 1 is a longitudinal sectional elevation of a portion of one half of a four plate wide cylinder, having one form of the invention applied thereto and

Fig. 2 is an end elevation thereof.

Figs. 3, 4 and 5 are sectional elevations of details of the locking mechanism.

Fig. 6 is an end elevation of a portion of the cylinder.

Fig. 7 is a view similar to Fig. 1 but showing a modified form of the invention, and

Fig. 8 is an end elevation thereof.

Figs. 9 and 10 are sectional elevations of details of the locking mechanism drawn to a larger scale.

Fig. 11 is a view similar to Fig. 1 of a further form of the invention adapted for use in locking stereo plates of varying widths and

Fig. 12 is a sectional view of a detail of the locking mechanism drawn to a larger scale.

Referring first to Figs. 1-6 inclusive. It will be understood that Fig. 1 represents the upper portion of one half only of a four plate wide cylinder 1 showing two plates 19, 20, the centre margin 18, and one set of locking means for these two plates only. In the complete cylinder similar plates and locking means are provided on the other upper half and also on the lower halves of the cylinder. The pairs of plates are locked by a series of dogs arranged in grooves around the periphery of each half of the cylinder, the operating means being arranged around the corresponding halves of the end

plates as shown in Fig. 2. The other half of the periphery will have two more pairs of plates with a similar series of dogs and grooves and the locking means will be arranged around the lower half of the end plates as shown in Fig. 2. The locking means on each end plate are exactly the same. The following description refers to the upper portion of one half only of the cylinder 1.

As shown the half cylinder 1 is provided with two sets of dogs 2 and 3 slidably mounted in grooves 6. From Fig. 2 it will be seen that there are four sets of grooves 6 each with a set of dogs therein.

Since the construction and operation of each set of dogs is the same, only one set will be described with reference to Fig. 1. The dog 3 is mounted on an externally threaded hollow sleeve 5, the outer end of which is flanged and formed with gear teeth 5a. Through this sleeve a rod 4 passes freely, having a screwed end which engages a screwed opening in the dog 2. The screwed portions of the rod 4 and the sleeve 5 have the same number of threads per inch and the outer end of the rod is flanged and formed with gear teeth 4a, equal in number to the teeth 5a. The rod 4 is supported in the end plate 15 and a packing piece 16 is introduced between the end of the cylinder and the plate to form an annular recess for containing the various gear wheels. As shown in Fig. 2 in which the plate 15 is partially broken away there are four rods 4 and between each pair of rods a pair of gear wheels 7 and 8, Figs. 2 to 6, are mounted which gear with the wheels 5a and 4a respectively on the adjacent rods. Each pair of wheels 7 and 8 are mounted as shown in Fig. 4, that is to say the wheel 7 is integral with a spindle 7a supported in a hole in the cylinder end and in the end plate 15, while the wheel 8 is freely mounted on said spindle 7a. The pair of wheels 7, 8 mounted between the central pair of grooves 6 (Fig. 2) are intended to control the operation of the other wheels and to this end, as shown in Figs. 2, 3, 5 and 6 the spindle supporting the wheel 8 of this pair is squared at the outer end 8a and the wheel 8 is formed with a boss having clutch teeth 8b formed thereon. The squared end 8a of the spindle carries a sliding cap 9 having clutch teeth 9a adapted to engage the teeth 8b and the outer surface of the cap is squared. The squared portion 8a of the spindle is formed with two recesses (not shown) and spring pressed ball 13 inside the cap 9 is adapted to snap into one or other of the recesses to hold the cap either in clutching engagement with the wheel boss or out of engagement.

If the squared cap 9 be turned with a spanner or key when in the clutched position the wheels 7 and 8 will turn as one and will similarly turn all the wheels 4a and 5a on

the other rods 4. Fig. 5 shows the clutched position. If the cap 9 is turned when in the unclutched position (Fig. 3) then only the wheels 7 and 5a of the series will be rotated. 70

It will be seen that rotation of the wheels 7 and 8 simultaneously rotates the rods 4 and sleeves 5, and thus simultaneously moves the sets of dogs 2 and 3 backwards or forwards according to the direction of rotation of the wheels and since the sleeves and rods have screw threads of equal pitch the relative positions of the dogs in each set remains unchanged. If the cap 9 is turned in the unclutched position then only the sleeves 5 and consequently the dogs 3 will move. Thus an adjustment of the dogs 2 and 3 as a pair and of the dogs 3 as units is possible in each set. 75

In setting up the plates on the cylinder, plate 19 is laid in position in the margin ring 18 and with the cap 9 in the clutched position (Fig. 5) a spanner is applied thereto and the nut is turned to cause the dogs 2 and 3 to move forward until the dogs 2 are pressed home against the plate 19, locking it firmly. The plate 20 is then laid in position, the cap 9 is unclutched (Fig. 3) and again rotated causing only the dogs 3 to move up and secure the plate 20. If the cap 9 is clutched and turned in the opposite direction, the plate 20 will be moved away releasing the plate 19, but it will still be firmly held on the cylinder and when the plate 19 has been removed the cylinder can be safely rotated for operations on the opposed half if desired. If the cap is unclutched and rotated in the opposite direction then only the dogs 3 are released and the plate 20 can be removed without disturbing the plate 19. 80

Thus it will be seen that the plate 19 can be secured without the usual distance piece which is usually pushed up against the dog 2 according to present practice to hold the plate 19 when the plate 20 has been removed to allow the cylinder to be rotated. In the present case the distance piece 21 Fig. 1 is only needed to fill up the grooves 6 between the dogs 2 and 3 to support the underside of the plate 20 where it bridges the grooves. 85

Referring now to Figs. 7-10 inclusive. In this case the plates 19, 20 are held in position by the dogs 22, 23 slidably in the grooves 6 and by the centre margin ring 18 as before. The dogs 22, 23 are mounted on screwed spindles 24 supported at their outer ends in a thrust plate 26 slidably mounted on the spindle of the cylinder. The dogs 23 are tapped but the dogs 22 are plain drilled. Each spindle 24 is formed with a gear wheel 24a and the gear wheels are interconnected round the half of the cylinder end by the gear wheels 28 and 30. The screwed ends of the spindles 24 engage tapped collars 27 and the 90

125

130

outer ends of the spindles pass through the thrust plate 26 and carry squared caps 25. Distance pieces 28b are provided. The gear wheel 28 is loosely mounted on a shoulder 32a on the thrust plate screw 32 (Fig. 9) and bears against a tapped collar 29 as shown.

The gear wheels 30 are loosely mounted on thrust plate guide pins 31 (Fig. 10).

- 10 With the above described arrangement, if one of the squared caps 25 be turned in the proper direction only the dogs 23 will move, the dogs 22 remaining in position. Thus the plate 20 can be removed without disturbing the plate 19, but if the cylinder is to be turned without removing the plate 19 then the latter can be locked by turning the cap 25 to cause the dogs 23 to force the distance piece 28b, into locking engagement with the dogs 22.
- 20 To remove the inside plates 19 without removing the plates 20, the squared end of the thrust plate screw 32 is appropriately turned. This causes the thrust plate to be withdrawn from the body of the cylinder simultaneously withdrawing the dogs 23, 22. Thus the plates 19 are released and can be removed while the plates 20 remain locked to the cylinder.

The above described arrangement is for use 30 with stereo plates of constant width or of varying width.

Figs. 11 and 12 inclusive show an arrangement for use with stereo plates in which the number of columns are varied.

- 35 In this arrangement the plates 19, 20 are held by the centre margin ring 18 and dogs 22, 23 as before and the dogs are operated by a thrust plate 26 and screwed spindles 24 and gear wheels 24a, 30 as in Figs. 7-10. But 40 to allow for the varying size of the plates clutch members are introduced into the spindles 24 to facilitate the setting of the dogs 22, 23. As shown in Figs. 11 and 12, slideable clutch member 33 is mounted on the 45 geared spindle 24, a key 34 ensuring that the clutch member 33 rotates with the spindle. The clutch member 33 is formed with teeth 39 and tommy holes 38 and a spring pressed ball 35 is fitted into the spindle adapted to 50 engage with either of the pockets 36, 37 formed in the clutch member. The inner dog 22 is tapped and mounted on a screwed spindle 41, which is a continuation of the spindle 24 and carries a clutch member 42 secured 55 to the spindle 24 by a screw 40. The pitch of the thread of the spindle 41 is half that of the spindle 24. The clutch member 42 is formed with tommy holes 44 and teeth 43. A small clearance is provided on each side 60 of the head of the screw 40 so that the spindle 24 can rotate freely and independently of the clutch member 42.

With the clutch member 42 and 33 disengaged the operations are as previously described with reference to Figs. 7-10 inclusive,

the screw 40 in conjunction with the clutch member 42 and the dog screw 41 serving the same purpose as the collars 27 in Fig. 7.

The operation for changing over to the different column widths of stereo plates is as follows:—

The clutch member 33 is moved along the spindle 24 until the teeth 39 engage the teeth 43 of the fixed clutch member 42. Then by operating one of the squared caps 25, the dogs 22, 23 are moved along the grooves to a working position suitable for narrower or wider plates, the dogs 22 traversing half the distance of the dogs 23. The clutch members 33 are disengaged when the change over is completed and are restrained from end movement by the ball 35 engaging the pocket 36. The clutch member 42 may be used to effect a fine individual setting of the dogs 22 by inserting a tool in the tommy holes 44 and turning the screws 41.

Although locking means employing separate dogs has been described it will be understood that the series of dogs may be constructed and mounted in any other suitable manner to accomplish the purposes of this invention.

Having thus described the nature of our said invention and the best means we know of carrying the same into practical effect, we claim:—

1. Means for locking printing plates on a printing cylinder, comprising a plurality of independent locking dogs adapted to be movably mounted on a printing cylinder for engagement respectively with the several plates thereof, means for independently operating one of the dogs to release one of the printing plates from the cylinder, and connecting means for causing simultaneous operation of the dogs for releasing a second plate from the printing cylinder.

2. Means for locking printing plates on a printing cylinder, comprising inner and outer locking dogs adapted to be mounted on a cylinder between inner and outer plates thereof for holding the plates to the cylinder, independent screw members mounted on the cylinder and operable from the end thereof and connected independently to said locking dogs, means for turning one of said screw members for moving the respective dog to release one of said plates independently of the other, and coupling means between the screw elements for simultaneously operating the same to free a second plate independently of the first plate.

3. Means for locking printing plates on a printing cylinder, comprising a central margin ring, a pair of spaced locking dogs mounted on the cylinder, said dogs and ring adapted to receive therebetween inner and outer printing plates, independent operating means operable from the end of the cylinder and connected to said dogs, one of said

means adapted for actuation to release the outermost dog to free the outer plate without releasing the inner plate, and coupling means for said operating means for simultaneously actuating the latter to move both of said dogs to maintain the outer plate in engagement with the cylinder and to free the inner plate therefrom.

4. Locking means for printing plates on a printing cylinder, comprising a cylinder body having longitudinal grooves therein, a central margin ring on the cylinder at the inner end of the groove, a pair of locking dogs slidably mounted in the groove, independent threaded means operable from the end of the cylinder and extending into the groove and connected to said locking dogs for independently actuating the same to clamp inner and outer plates on the cylinder, one of said operating means adapted for operation to release the outer dog and free the outer plate, and coupling means for said operating means to actuate the same simultaneously to free the inner plate from the margin ring and the inner dog without freeing the outer plate.

5. Means for locking printing plates on a printing cylinder, comprising a cylinder having a central margin ring and a groove extending lengthwise from the end of the cylinder, inner and outer locking dogs slidably mounted in said groove of the cylinder and adapted to hold inner and outer printing plates between the dogs and the inner dog and the margin ring, an internally threaded sleeve carried by the outer dog, a second internal sleeve carried by the inner dog, a rod extending from the end of the cylinder and having threads upon its inner end engaging in the sleeve of the inner dog for moving the dog when the rod is turned, a threaded hollow rod around said first rod and freely movable thereon and engaged in threaded relation with the sleeve of the outer dog for moving the latter when the outer rod is turned, means for turning said outer rod to move the outer dog and release the outer plate, and means for simultaneously moving the inner and outer rods for simultaneously moving said inner and outer dogs to hold the outer plate in interlocked engagement on the cylinder and for freeing the inner plate therefrom.

6. Means for locking printing plates on a printing cylinder, comprising a cylinder body having a longitudinal groove therein and a central margin ring, a pair of locking dogs slidably mounted in the groove of the cylinder and adapted to engage inner and outer plates between the ring and the inner dog and between the inner and outer dogs, a threaded shaft in said groove extending from the end of the cylinder and threaded through the outer dog and slidably engaging through the inner dog, an abutment car-

ried upon the inner end of the threaded shaft to engage the inner dog, means for turning the shaft to adjust the outer dog, and means for moving the shaft longitudinally in the groove for moving both the inner and outer dogs.

In testimony whereof we have signed our names to this specification.

MATTHIAS LEWIS WILKINSON.
ROBERT BRADSHAW.
